UNITED STATES PATENT OFFICE.

MOSE MARKS, OF OMAHA, NEBRASKA, ASSIGNOR TO THE OMAHA SADDLE-TREE COMPANY, OF DOUGLAS COUNTY, NEBRASKA.

DESIGN FOR A HORN FOR SADDLETREE-FORKS.

SPECIFICATION forming part of Design No. 32,205, dated February 6, 1900.

Application filed January 6, 1900. Serial No. 628. Term of patent 14 years.

To all whom it may concern:

Be it known that I, MOSE MARKS, a citizen of the United States, residing at Omaha, in the county of Douglas and State of Nebraska, have invented and produced a new and original Design for a Horn for a Saddletree-Fork, of which the following is a specification, reference being had to the accompanying drawing, forming part thereof.

The drawing is a perspective view of a horn for a saddletree-fork, showing my new design.

As shown in the drawing, the leading or material feature of my design consists of a head 1, surmounting a tapering neck 2. At the base of the neck is a forward projection

3, back of which and on a line therewith are triangular-shaped projections 4, into which the back of the neck 2 merges, as shown in the drawing. Projecting outwardly and downwardly from a point between the projections 20 3 and 4 are curved legs 5.

Having described my invention, what I claim as new, and desire to secure by Letters Patent, is—

The design for a horn for a saddletree-fork, 25 as herein shown and described.

MOSE MARKS.

In presence of—
JOHN STEINERT,
A. C. ASH.
